(57) **CLAIM**

The ornamental design for a rectangular extrusion for lighting fixtures, as shown and described.

DESCRIPTION

FIG. 1 is a front elevational view of the rectangular extrusion for lighting fixtures showing our new design;

FIG. 2 is a rear elevational view thereof;

FIG. 3 is a bottom perspective view thereof, shown in a closed position of use;

FIG. 4 is a bottom perspective view thereof, shown in an open position of use;

FIG. 5 is a right side elevational view thereof;

FIG. 6 is a bottom plan view thereof;

FIG. 7 is a left side elevational view thereof; and,

FIG. 8 is a top plan view thereof.

The rectangular extrusion for lighting fixtures is shown broken away on one end to indicate no specific length.
